CLAIM

The ornamental design for a sink for corner mounting, as shown and described.

DESCRIPTION

FIG. 1 is a top perspective view of a sink for corner mounting, showing my new design;

FIG. 2 is a top plan view thereof;

FIG. 3 is a front elevational view, the rear view bearing a mirror image thereof; and,

FIG. 4 is a top plan view of a second embodiment, the front and rear views being identical to that shown in FIG. 3.
